CLAIM

The ornamental design for a monitor for computer, as shown and described.

DESCRIPTION

1.. Monitor for computer

1.1 : Front perspective view

1.2 : Front view

1.3 : Back view

1.4 : Left side view

1.5 : Right side view

1.6 : Top view

1.7 : Bottom view

1.8 : Back perspective view

1.9 : Right side view showing a first alternate configuration

(Continued)

1.10 : Top view showing a second alternate configuration
The oblique shade lines on the drawings indicate the display
part. The broken lines in the drawings depict portions of the
monitor for computer that form no part of the claimed
design.

1 Claim, 10 Drawing Sheets
